(57) **CLAIM**

The ornamental design for a water treatment device, as shown and described.

DESCRIPTION

FIG. 1 is a perspective view of the water treatment device; FIG. 2 is a front elevational view of the water treatment device;

FIG. 3 is a rear elevational view of the water treatment device;

FIG. 4 is a side elevational view of the water treatment device, the opposite side of which is an identical mirror image;

FIG. 5 is a top plan view of the water treatment device; and, FIG. 6 is a bottom plan view of the water treatment device. The broken lines shown on the drawings are for illustrative purposes only and form no part of the claimed design.
